The ornamental design for a wheel, as shown and described.

DESCRIPTION

FIG. 1 is a perspective view of a wheel;

FIG. 2 is a left view of the wheel of FIG. 1;

FIG. 3 is a right view of the wheel of FIG. 1;

FIG. 4 is a front view of the wheel of FIG. 1;

FIG. 5 is a back view of the wheel of FIG. 1

FIG. 6 is a top view of the wheel of FIG. 1; and,

FIG. 7 is a bottom view of the wheel of FIG. 1.

The evenly dashed broken lines shown in drawings are for the purpose of illustrating portions of the wheel and forms no part of the claimed design. The short dash long dash broken lines define the bounds of the design and forms no part of the claimed design.

1 Claim, 5 Drawing Sheets(56)
